No. 817,758.

PATENTED APR. 17, 1906.

N. R. EVANS.

GREENHOUSE SASH OPENER.

APPLICATION FILED FEB. 13, 1905.

UNITED STATES PATENT OFFICE.

NEWTON R. EVANS, OF RICHMOND, INDIANA, ASSIGNOR TO JOHN A. EVANS, OF RICHMOND, INDIANA.

GREENHOUSE-SASH OPENER.

No. 817,758.

Specification of Letters Patent.

Patented April 17, 1906.

Application filed February 13, 1905. Serial No. 245,553.

To all whom it may concern:

Be it known that I, NEWTON R. EVANS, a citizen of the United States, residing at Richmond, in the county of Wayne and State of Indiana, have invented certain new and useful Improvements in Greenhouse-Sash Openers, of which the following is a specification.

This invention relates to improvements in means for opening and closing the sashes for greenhouses for the purpose of ventilation and to means for holding any given adjustment of the sash.

The object is to provide means for simultaneously opening and closing a number of such sashes and to render same operative at the expenditure of the minimum amount of effort on the part of the operator.

The invention consists of certain novel and advantageous features such as will be herein-after described, and particularly set forth in the subjoined claims.

I accomplish the objects of the invention by the mechanism illustrated in the accompanying drawings, in which—

25 Figure 1 is a side elevation of my improved device; Fig. 2, a vertical section longitudinally of the horizontal shaft through the top sprocket and the bearings in which said sprocket is mounted. Fig. 3 is a detail in 30 vertical section on the line 3 3 of Fig. 1 looking in the direction of the arrows. Fig. 4 is a detail in vertical section on the dotted line 4 4 of Fig. 2 looking in the direction of the arrows. Fig. 5 is a detail view of part of the 35 operating mechanism, and Fig. 6 is a detail of a modified form of rod used as a chain extension to connect the link or chain of the upper and lower sprocket-wheels.

40 Like characters of reference indicate like parts throughout the several views of the drawings.

7 represents the vertical supporting-post, which is preferably made of iron tubing and supported at its bottom upon the base 8. The 45 base 8 will preferably be of cast-iron having the upwardly-projected toe 9, which enters the lower end of pipe 7.

10 is a bearing-box having the downwardly-extended sleeve 11, the bore of which 50 sleeve is screw-threaded, and into it is screwed the threaded top end of the tubular post 7. A given adjustment of the post within said sleeve is retained by means of the set-screw 12.

13 is a sprocket-wheel which has the hub 55 extension 14 on one side and a hub extension 15 on its opposite side. The entire hub thus formed has a bore for passage of the horizontal tubular shaft 16. The hub extension 14 has an enlargement of its bore to make room 60 for the insertion of a gib 17. This gib has a concave face which bears against the shaft 16, and a close-holding contact of the gib with the shaft is obtained by means of the set-screws 18, which pass through the threaded 65 openings in the wall of the hub 14 and bear against said gib in the manner as clearly shown in Fig. 2. Inasmuch as the attachment of the sprocket-wheel 13 to shaft 16 is made through hub 14 it becomes important 70 to provide ample means for making this attachment secure, and for that reason I provide the two set-screws 19 through the hub 14 at points diametrically opposite the gib 17. The hub extension 15 is cylindrical and 75 is inserted within the box 10, above mentioned, and is enough less in diameter to permit of the introduction around said hub 17, between it and the box 10, of the cylindrical metal pins 22, which form roller-bearings to 80 reduce the friction between the hub and said box. This is an important feature of my invention. The pins are retained in the above-described position in box 10 by means of the collar 24, which is moved up against the end 85 of the box and is retained on the hub by means of the set-screw 25.

The upper end of the post 7 is held rigid against vibration by means of the brackets 26. The box 10 has a transverse slot approximately in alignment with the axis of post 7, and in this slot the annular end of the bracket 26 is introduced. The recess in the lower end of the bracket conforms in diameter to the diameter of hub 10 and in practice forms a 95 part of the box or housing to receive the pins 22, and by this construction the bracket is adjustedly secured to the hub 15 of the sprocket 13. Projecting from the side of the bracket 26 is the flange 28, which with the continuation of the bracket forms a holding member with two sides at right angles to each other to embrace the corner of a rafter of the greenhouse, to which said members of the bracket are secured by suitable bolts or screws. 100

The sleeve 11 has a vertical rib 29 adjacent to the sprocket-wheel 13 to form a stop to regulate the extent of the rotation of said 105

wheel. This is effected by providing the wheel 13 with the laterally-extended lugs 30, which by contacting with the flange 29 prevent further movement in a given direction 5 of said wheel, and in order that the amount of this movement may be regulated I make the lugs 30 adjustable in their distances from each other. This adjustment is secured by providing concentric slots 32 through the web 10 of the wheel 13, through which slots the reduced threaded ends of the removable lugs 30 are passed and the lugs secured in a given position by means of nuts which are screwed upon the said reduced ends.

15 The line-shaft 16 is connected with the sashes of the greenhouse by means of a series of jointed arms 34, as is common in this class of devices, and the adjustment of the lugs 30, as described in the last paragraph, 20 enables the lugs to be set so as to allow the wheel 13 to move a distance that will move the sashes the desired extent.

25 The sprocket-wheel 13 is connected with and driven by a suitable mechanism for operating the line-shaft 16. One form of such a mechanism is shown in the drawings and consists of a short horizontal shaft 36, which has its bearings in a suitable bracket 37, which is fastened in position around the post 30 7. The shaft 36 has a sprocket-wheel 38 at one end, which is connected by an endless sprocket chain or belt 39 with said sprocket-wheel 13, and the opposite end of shaft 36 has the worm-wheel 40, which meshes with a 35 worm 41 on the inner end of the shaft 42, which is mounted at right angles to the shaft 36 and has at its opposite end a suitable hand-wheel 43 for operating the device.

40 Inasmuch as the sprocket-wheel 13 has a rocking movement instead of a continuous rotary one, only a portion of the length of the sprocket-chain 39 is made to travel around either of the said sprocket-wheels 13 or 38. Consequently I am able to economize in the 45 cost of the construction of chain 39 by utilizing a sufficient length of chain belt to go around and operate with wheels 13 and 38 in their limited movements and connect said top and bottom chain-sections by means of 50 rods or bars 45. Pivotal secured to the ends of the above-mentioned sections of chain are the metal sockets 46, in which the ends of the bars 45 are inserted and are there held by means of the set-screws 47. This while 55 cheapening the cost of construction also affords an easy means of adjusting the length of the belt to suit the particular requirement of the job. By making the bars 45 of ample length primarily an end can be cut off to reduce them to the length desired and the new end inserted into the socket and there retained by means of the screws. In the modification shown in Fig. 6 this cheapening of the chain by the introduction of rod lengths is 60 carried out in a somewhat different manners

from that just described and as shown in Figs. 1 and 3. In the modification shown in Fig. 6 the thickness of the rod 50 is supplemented by plates 51, so as to fill out the space between the sides of a link to which it is to be 70 fastened, and it is pivotally secured to that link by means of a pin or rivet, as shown.

Having thus fully described my invention, what I claim as new, and wish to secure by Letters Patent of the United States, is—

75 1. The combination, with the post, of a bearing-box at the top of the post, a line-shaft passing through said box, a sprocket-wheel mounted on the line-shaft, said sprocket-wheel having a hub extension which passes 80 through the bearing-box, cylindrical bearing-pins in annular series between the sleeve and bearing-box, a collar fastened to the projecting end of the hub extension and bearing against the bearing-box to hold the 85 parts together, window-sashes, means for connecting said line-shaft with said window-sashes, means for regulating the extent of movement of said sprocket-wheel, and means connected with the said sprocket-wheel for 90 operating said line-shaft.

2. A base having a toe, a tubular post engaging said toe and resting on said base, a bearing-box having a threaded sleeve into which the threaded top end of said post is 95 screwed, means for holding a given adjustment of the sleeve with the post, a line-shaft passing through said bearing-box, a sprocket-wheel mounted in a fixed manner on the line-shaft and having a cylindrical hub extending 100 into and through the bearing-box, cylindrical bearing-pins between the hub and bearing-box, means for retaining the pins in position between the hub and box, window-sashes means for connecting said line-shaft with said 105 window-sashes, and means connected with said wheel for operating said line-shaft.

3. The combination, with a post, a bearing-box at the top of the post having a transverse vertical slot, a bracket attached to a fixed support entering the slot in said bearing-box said bracket having a perforation of the same diameter as the bore of the said box, a horizontal shaft passing through the bearing-box and bracket, a sprocket-wheel mounted on 110 the shaft said wheel having a hub-extension which passes through the bearing box, and roller-bearings between the hub extension and the bearing-box.

4. In a device for the purposes specified, a 115 post, a horizontal bearing-box at the top end of said post having a transverse slot between its ends, in combination with a line-shaft passing through said bearing-box, a bracket inserted in said slot of the bearing-box through 120 which bracket said shaft also passes said bracket being attached to a fixed support, a sprocket-wheel mounted in a fixed manner on 125 said shaft and having a cylindrical hub extending into said bearing-box, cylindrical 130

bearing-pins between the hub and bearing-box, means for operating said sprocket-wheel, means for regulating the movement of the said sprocket-wheel hinged window-sashes 5 and arms on the line-shaft connected with said window-sashes.

5. A post, a bearing-box having a threaded sleeve which is screwed onto the top of the post, a line-shaft passing through the bearing-
10 box, a sprocket-wheel mounted on the line-
shaft, said sprocket-wheel having a hub with
an enlargement in the bore of the hub, a gib
inserted in said bore enlargement of the hub,
set-screws for locking the hub and gib to the
15 shaft, said sprocket-wheel also having a cy-
lindrical hub extension which enters the said
bearing-box, cylindrical bearing-pins between
the last hub extension and the bearing-box,
the sleeve of said bearing-box having a flange
20 adjacent to the sprocket-wheel, lugs on the
side of the sprocket-wheel adjacent to said
flange on the sleeve, said lugs being adjust-
able in distance from each other and being
adapted to contact with the flange of said
25 sleeve to control the movement of the wheel,
means for connecting said line-shaft with

window-sashes and means connected with
said wheel for operating said line-shaft.

6. In a device for the purpose specified, a
post, a bearing-box supported by said post, a 30
line-shaft passing through said bearing-box,
means connecting said line-shaft with win-
dow-sashes, a sprocket-wheel mounted on said
line-shaft, a second sprocket-wheel mounted
below the line-shaft, means for operating the 35
lower sprocket-wheel and means for connect-
ing the two sprocket-wheels said last means
comprising chain-belt sections to operate with
said sprocket-wheels and terminating with
40 metal sockets, and bars having their ends in-
serted in said sockets and set-screws securing
them therein so as to connect the ends of the
top chain-section with the corresponding ends
of the bottom chain-section.

In witness whereof I have hereunto set my 45
hand and seal at Indianapolis, Indiana, this
4th day of February, A. D. 1905.

NEWTON R. EVANS. [L. S.]
